DESIGN FOR A FILE HOLDER

Frank A. Seedlock and Edward L. Noll,
Lakewood, Ohio

Application March 5, 1941, Serial No. 99,358

Term of patent 7 years

To all whom it may concern:

Be it known that we, Frank A. Seedlock and Edward L. Noll, citizens of the United States, residing at Lakewood, in the county of Cuyahoga and State of Ohio, have invented a new, original, and ornamental Design for File Holders, of which the following is a specification, reference being had to the accompanying drawing, forming part thereof, and wherein Fig. 1 is a side elevational view of a file holder showing our new design; Fig. 2 a plan view; Fig. 3 a perspective view, and Figs. 4 and 5 are details in section taken on the lines 4—4 and 5—5, respectively, of Fig. 3.

We claim:

The ornamental design for a file holder, as shown.
